UNITED STATES PATENT OFFICE.

HENRY J. NUTRIZIO, OF NEW YORK, N. Y.

DESIGN FOR A DISPLAY REST FOR SHOES OR THE LIKE.

Application filed April 12, 1922. Serial No. 1,695. Term of patent 3½ years.

To all whom it may concern:

Be it known that I, HENRY J. NUTRIZIO, a citizen of the United States, residing in the city, county, and State of New York, have invented a new, original, and ornamental Design for Display Rests for Shoes or the Like, of which the following is a specification, reference being had to the accompanying drawings, forming a part thereof, and of which—

I claim:

The ornamental design for a display rest for shoes or the like as shown.

HENRY J. NUTRIZIO.
